(57) **CLAIM**

I claim, the ornamental design for a webcam cover, as shown and described.

DESCRIPTION

FIG. 1 is a top, front, right perspective view of a webcam cover showing the new design,

FIG. 2 is a front view thereof,

FIG. 3 is a rear view thereof,

FIG. 4 is a top view thereof,

FIG. 5 is a bottom view thereof,

FIG. 6 is a right side view thereof,

FIG. 7 is a left side view thereof,

FIG. 8 is a longitudinal-sectional view of the webcam cover taken along line 8-8 in FIG. 2,

FIG. 9 is a cross-sectional view of the webcam cover taken along line 9-9 in FIG. 2,

FIG. 10 is a perspective view of FIG. 1 in an open position,

FIG. 11 is a front view of FIG. 10,

FIG. 12 is a rear view of FIG. 10,

FIG. 13 is a top view of FIG. 10,

FIG. 14 is a bottom view of FIG. 10,

FIG. 15 is a right side view of FIG. 10,

FIG. 16 is a left side view of FIG. 10,

FIG. 17 is a perspective view of the right portion of FIG. 1 with the left portion of FIG. 1 removed to show aspects of the design that are not visible when combined,

FIG. 18 is a front view of FIG. 17,

FIG. 19 is a rear view of FIG. 17,

FIG. 20 is a top view of FIG. 17,

FIG. 21 is a bottom view of FIG. 17,

FIG. 22 is a right side view of FIG. 17,

FIG. 23 is a left side view of FIG. 17,

FIG. 24 is a perspective view of the left portion of FIG. 1 with the right portion of FIG. 1 removed to show aspects of the design that are not visible when combined,

FIG. 25 is a front view of FIG. 24,

FIG. 26 is a rear view of FIG. 24,

FIG. 27 is a top view of FIG. 24,

FIG. 28 is a bottom view of FIG. 24,

FIG. 29 is a left side view of FIG. 24; and,

FIG. 30 is a right side view of FIG. 24.
